COMBINED ASH TRAY RECEPTACLE AND CARD TRAY OR SIMILAR ARTICLE

Karl Domberger, Maspeth, and Sol Rael,
Jackson Heights, N. Y.

Application May 9, 1955, Serial No. 35,878

Term of patent 3½ years

(Cl. D85—2)

Figure 1 is a perspective view of a combined ash tray receptacle and card tray, or similar article, showing our new design;

Figure 2 is a similar view thereof with the card tray in extended position;

We claim:

The ornamental design for a combined ash tray receptacle and card tray or similar article, as shown.
